(57) **ABSTRACT**

An x-ray tube, comprising: a field emitter including an emission surface; an anode; and a focus electrode disposed between the field emitter and the anode; wherein: the focus electrode includes: a first surface that is substantially perpendicular to the field emitter emission surface and nearest to the field emitter; a second surface that is axially nearest to the anode, wherein the field emitter and the anode form an axis; and a third surface that extends between the first surface and the second surface; and a first location on the focus electrode between the first surface and the third surface is further from the anode than a second location on the focus electrode between the third surface and the second surface.

X-RAY SYSTEM WITH FIELD EMITTERS AND ARC PROTECTION

X-ray tubes used within x-ray systems may include field emitters. Field emitters may be particularly susceptible to arcing due to the structure of the field emitters. An arc that impacts the field emitter may degrade or destroy the structure and eventually render the x-ray tube inoperable.

BRIEF DESCRIPTION OF SEVERAL VIEWS OF THE DRAWINGS

FIG. 1 is a block diagram of an x-ray tube according to some embodiments.

FIG. 2 is a block diagram of an x-ray system according to some embodiments.

FIG. 3 is a block diagram of an x-ray tube with a two surface electrode according to some embodiments.

FIG. 4 is a block diagram of an x-ray tube with a three surface electrode according to some embodiments.

FIG. 5 is a block diagram of an x-ray tube with a focus electrode having a protrusion according to some embodiments.

FIG. 6 is a cutaway view of a focus electrode according to some embodiments.

FIG. 7 is a cutaway view of a focus electrode for multiple field emitters according to some embodiments.

FIG. 8 is a cross-sectional view of a cathode assembly including a focus electrode according to some embodiments.

FIG. 9 is a block diagram of a x-ray imaging system according to some embodiments.

DETAILED DESCRIPTION

Some embodiments relate to x-ray systems and x-ray tubes with field emitters and arc protection. Field emitters may be particularly susceptible to arcing and damage due to the structure. The relative size of field emitters may otherwise increase an electric field strength at the field emitter. The increased electric field strength may increase a probability that an arc may occur and may increase a probability that the arc occurs on the field emitter. As will be described in further detail below, position and structure of a focus electrode may reduce a probability that an arc may occur on the field emitter and cause damage. In addition, if an arc occurs, the likely position of the arc may be controlled to be further from the field emitter. As a result, a probability that the x-ray tube may remain operable after an arc may increase.

FIG. 1 is a block diagram of an x-ray tube according to some embodiments. The x-ray tube 100a includes an anode 102, a field emitter 104, and a focus electrode 106a. The anode 102 includes a structure configured to generate x-rays in response to incident electrons. The field emitter 104 is configured to generate an electron beam that may be directed towards the anode 102. The field emitter 104 may include a variety of types of emitters. For example, the field emitter 104 may include a nanotube emitter, a nanowire emitter, a Spindt array, or the like. Conventionally, nanotubes have at least a portion of the structure that has a hollow center, where nanowires or nanorods has a substantially solid core. For simplicity in use of terminology, as used herein, nanotube also refers to nanowire and nanorod. A nanotube refers to a nanometer-scale (nm-scale) tube-like structure with an aspect ratio of at least 100:1 (length:width or diameter). A Spindt array may include individual field emitters with small sharp cones using an electron generating material, such as

molybdenum (Mo) or Tungsten (W). In some embodiments, the field emitter 104 is formed of an electrically conductive or semi-conductive material with a high tensile strength and high thermal conductivity such as carbon, metal oxides (e.g., Al_2O_3 , titanium oxide (TiO_2), zinc oxide (ZnO), or manganese oxide (Mn_xO_y , where x and y are integers)), metals, sulfides, nitrides, and carbides, either in pure or in doped form, or the like.

In some embodiments, the field emitter 104 may include multiple field emitters. For example, the field emitter 104 may include, tens to hundreds or more of individual field emitters 104. Each field emitter 104 may be configured to generate an electron beam directed towards the anode 102. Each field emitter 104 may be associated with corresponding focus electrodes 106, such as the focus electrodes pair 106a, 106 shown in FIG. 1, or a corresponding opening of a unitary focus electrode 106.

Field emitters 104 may have areas that are larger relative to other types of emitters. For example, a field emitter 104 may have length of about 10 millimeters (mm) to about 30 mm and a width from about 2 mm to about 6 mm. In an example, the length of the field emitter 104 is at least 5 times larger than the width. The larger relative area may result in a larger size of a focal spot on the anode 102. Heating of the anode 102 due to incident electrons on the focal spot may be spread over that larger area, decreasing the thermal stress on the anode 102, permitting a higher electron flux, or the like. In addition, field emitters 104 may have a relatively lower current flux as compared to other emitters. To compensate for the lower flux, the area of the field emitter 104 may be increased. These aspects lead to larger relative areas for field emitters 104. The larger relative area means that the local field strength around the field emitter 104 is more sensitive to the anode 102 or tube voltage.

The larger relative area of a field emitter 104 may increase a probability of an arc. As the area of the field emitter 104 increases, a relative position of another structure that may receive an arc is moved further away from the anode 102, decreasing the electric field strength on those structures relative to the electric field strength at the field emitter 104. As a result, a probability that an arc may occur at the field emitter 104 may increase. Field emitters 104 may be more sensitive to arcing than other types of emitters, such as thermionic emitters, due to their structure. For example, field emitters 104 may include relatively small structures, such as a thin layer, that may be damaged by an arc.

Accordingly, field emitters have competing design issues. The field emitter 104 may be larger in area due to its nature and due to a desired larger focal spot for distributed heating. However, that increased area increases the probability of arcing occurring on the field emitter 104.

The focus electrode 106a may alleviate the increased probability of arcing occurring on the field emitter 104. As a result, benefits of the larger area of a field emitter 104 may be realized while the probability of damage to the field emitter 104 due to arcing is reduced. The focus electrode 106a is disposed between the anode 102 and the field emitter 104. The focus electrode 106a is configured to adjust the size and/or shape of the focal spot on the anode 102. At least part of the focus electrode 106a is closer to the anode 102 than any part of the field emitter 104. For example, a shortest distance between any part of the field emitter 104 and any part of the anode 102 may be distance 108. A shortest distance from part of the focus electrode 106a to the anode 102 may be distance 110. Distance 110 is less than distance 108.

Due to the distance **110** to the focus electrode **106a** being shorter than the distance **108** to the field emitter **104**, the electric field strength at the focus electrode **106a** may be greater than the electric field strength at the field emitter **104**. As a result, a probability that an arc will occur on the field emitter **104** may be decreased while a probability that an arc will occur on the focus electrode **106a** may increase.

In some embodiments, the focus electrode **106a** is disposed relative to the field emitter **104** and the anode **102** and shaped such that during operation, a point of highest electric field strength on a cathode structure is closer to the focus electrode **106a** than the field emitter **104**. The cathode structure may include structures that are at or near the potential of the field emitter **104**. For example, the anode **102** may be at about 10-50 kilovolts (kV), about 50-150 kV, about 50-450 kV or the like (relative to the cathode structure or ground). In some embodiments, these voltages may be associated with particular applications, such as mammography, medical diagnostic imaging, industrial imaging, explosive detection, non-destructive testing (NDT), or the like. The cathode structure, such as the field emitter **104**, the focus electrode **106a**, a grid (not illustrated), or the like may be at voltages from about -3 kV to about 1 kV. Generally, a higher electric field strength may increase the probability of an arc. As a result, the design of an x-ray tube **100a** may include minimizing local electric field strength maxima. However, in some embodiments, the point of highest electric field strength can be created by design and, in particular, offset or shifted away from the field emitter **104**. In some embodiments, the electric field strength at the point of highest electric field strength may be greater than about 8 times the highest electric field strength on the field emitter **104**. In some embodiments, the structure of the focus electrode **106a** may result in the electric field strength at the point of highest electric field strength being at least about 25% higher than the electric field strength on a portion of the focus electrode **106a** closest to the field emitter **104**.

FIG. 2 is a block diagram of an x-ray system according to some embodiments. The x-ray system **200** may include an x-ray tube **100b** similar to x-ray tube **100a** described above. The x-ray tube **100b** may include a vacuum enclosure **212** where the anode **102**, field emitter **104**, and the focus electrode **106b** are disposed in an interior **202a** of the vacuum enclosure **212**.

The x-ray system **200** may include a voltage source **204** disposed on an exterior **202b** of the vacuum enclosure **212**. The voltage source **204** may be configured to generate multiple voltages for the x-ray system **200**. For example, the voltage source **204** may be configured to generate one or more voltages **206** for the field emitter **104**, a high voltage **208** for the anode **102**, a focus electrode voltage **210** for the focus electrode **106**, or the like.

In some embodiments, the focus electrode **106b** may be grounded. That is the focus electrode voltage **210** may be 0 V or near 0 V. Portions of the vacuum enclosure **212**, a housing for the x-ray tube **100b**, or the like may be grounded. The focus electrode **106b** may share that ground. In some embodiments, the voltage source **204** may share that ground. As a result, arcs that discharge through the focus electrode **106b** may direct the charge to ground.

In some embodiments, the focus electrode **106b** may be at a voltage **210** different from ground. For example, the voltage source **204** may be configured to apply a variable voltage to the focus electrode **106b**. The voltage source **204** may include spark gap protectors or other circuitry to allow for the desired variability in the focus electrode voltage **210** while still accommodating arcs that may occur.

FIG. 3 is a block diagram of an x-ray tube with a two surface electrode according to some embodiments, where two surfaces **302**, **306** of the focus electrode have a higher electric field strength than two other surfaces **308**, **310** that face away from the anode. The x-ray tube **100c** may be similar to the x-ray tubes **100a-b**. However, the focus electrode **106c** may have a particular structure.

The focus electrode **106c** may have a structure relative to an axis **300**. The field emitter **104** and the anode **102** may form the axis **300**. The axis **300** may be aligned in the general direction of the electrons emitted from the field emitter **104** traveling towards the anode **102**. In this example, the axis **300** may extend along the Y axis. A component that extends axially relative to the axis **300** may have some component along the Y axis. In some embodiments, an axially extending component may extend only axially or only along the Y axis while other axially extending components may have some part that extends radially, i.e., perpendicular to the axis **300** or the Y axis parallel to the X-Z plane, extends along the X axis, extends along the Z axis, or the like.

The focus electrode **106c** includes at least two surfaces. Here, two surfaces **302** and **304** are used as an example. The first surface (or field emitter perpendicular surface or beam shaping surface) **302** extends substantially parallel to the axis **300** or an emission surface of the field emitter **104**. The surface **302** may include the beam shaping surface with a structure that shapes a focal spot on the anode **102** when operating. The surface **302** may contribute to a majority of the shaping of the electric field to focus electrons from the field emitter **104** on the anode **102**. Other surfaces, such as surface **304** may have some impact, but the relative contribution of surface **304** is less than that of surface **302**.

The second surface (or anode facing parallel surface) **304** of the focus electrode **106c** extends radially away from the first surface **302** from the axis. In some embodiments, the second surface **304** is formed to extend only radially away parallel to the X-Z plane from the first surface **302** without a substantial axial component. As a result, the location **306** where the first surface **302** and the second surface join may be about a 90 degree angle. The second surface **304** may be a surface that is nearest to the anode **102**. During operation, a point of highest electric field strength is disposed where the first surface **302** joins the second surface **304**. As the focus electrode **106c** may be at the same potential, an electric field strength along surface **302** may be necessarily less than that of the location **306** where the first surface **302** and the second surface **304** join. In addition, the relatively sharp feature of the location **306** may increase the local electric field strength, as electric fields concentrate around the corners or edges of conductors in the field. As a result, an arc that may occur can have an increased probability of occurring at location **306** rather than on the field emitter **104**.

Although a 90 degree angle has been used as an example, in other embodiments, the angle may be different. For example, the angle may be larger or smaller in a range such that a local maximum of electric field strength on cathode structures occurs at the location **306**.

FIG. 4 is a block diagram of an x-ray tube with a three surface electrode according to some embodiments, where three surfaces **402**, **404**, **406** of the focus electrode have a higher electric field strength than other surfaces **414**, **416** that face away from the anode. The x-ray tube **100d** may be similar to the x-ray tubes **100a-c**. However, the focus electrode **106** may include at least three surfaces with a higher electric field strength. A first surface (or field emitter perpendicular surface or beam shaping surface) **402** may be

similar to the first surface 302 of focus electrode 106c of x-ray tube 100c. The first surface 402 may be a beam shaping surface that affects the focal spot.

A third surface (or anode facing surface) 408 may extend radially parallel to the X-Z plane away from the first surface 402 and is joined to the first surface 402 at location (or inner angle or inner corner) 406 similar to the second surface 304 of focus electrode 106c. However, the third surface 408 also extends axially away from the first surface 402 relative to the axis 300 along the Y axis. In this embodiment, the axial extension of the third surface 408 is in a direction towards the anode. As a result, the angle of the first surface 402 and the third surface 408 at location 406 may be greater than 90 degrees. If the angle at location 406 is greater, the electric field strength at location 406 may be reduced relative to an angle of 90 degrees. Similar to the first surface 402, the third surface 408 is a beam shaping surface and helps to shape the electron beam to a desired cross section with a desired trajectory on a focal spot on the anode 102 when operating.

In addition, the focus electrode includes a second surface (or anode facing parallel surface) 404. The second surface 404 joins the third surface 408 at location (or outer angle or outer corner) 410. The second surface 404 extends away from the third surface 408 relative to the axis 300. The resulting structure allows for both control of the focal spot through surface 402, but also positioning of a point of higher electric field strength further away from the field emitter 104 by the angle at location 406, the length of the third surface 404, and the angle at location 410.

For example, line 412 is a point equidistant from the anode 102. Location 410 where the third surface 408 joints the second surface 404 may be at the equidistant line 412. However, the location 406 may be further from the anode 102 than the equidistant line 412. As a result, an electric field strength at the location 406 may be lower than the electric field strength at the location 410. A point of highest electric field strength may be disposed at location 410 where the third surface 408 joins the second surface 404.

In addition, the angle of the second surface 404 to the third surface 408 at location 410 may be determined such that other points along the second surface 404 are further from the anode 102 than the point 410. As a result, an electric field strength along the surface 404 may be less than the electric field strength at the location 410. The electric field strength along the focus electrode 106d may be a local maximum at the location 410. Any arcing may occur at the location 410, rather than other locations along the focus electrode 106d including those closer to the field emitter 104. Due to the close proximity of location 306 (FIG. 3) relative to the field emitter, arcing at the highest electric field strength location 306 may still leak or arc to surrounding features, such as the field emitter 104 causing damage to the field emitter 104. Moving the highest electric field strength to the location 410 (FIG. 4) away from the field emitter 104, reduces the likelihood that arcing at the highest electric field strength location 410 will leak or arc to the field emitter 104, thus reducing the likelihood of damage to the field emitter 104 due to arcing. For a similar sized focus electrodes 106c, 106d at a similar distance away from the anode 102, the location 306 (FIG. 3) with a sharper or narrower angle can be closer to the anode 102 with a higher electric field strength than the location 410 (FIG. 4) with a wider angle, so the focus electrodes 106c can have improved beam shaping and focusing characteristics but with an increased likelihood of arcs and damage to the cathode structures, such as field emitters 104, caused by arcs.

In some embodiments, the part or location (e.g., 410) of the focus electrode 106d that is closer to the anode 102 (e.g., with the highest electric field strength) than any part of the field emitter 104 is further from a center of the field emitter 104 than another part of the focus electrode 106d (e.g., 402, 406, 408). For example, beam shaping surfaces of the focus electrode 106d, such as surface 402 that face the electron beam, may be closer to a center of the field emitter 104 than that part or location (e.g., 410) of the focus electrode 106d (with the highest electric field strength). As the focus electrode 106d may be at a single potential, the electric field strength will be higher at the part or location (e.g., 410) of the focus electrode 106d that is closer to the anode 102 than the beam shaping surfaces (e.g., 402, 404, 408).

FIG. 5 is a block diagram of an x-ray tube with a focus electrode having a protrusion according to some embodiments. The x-ray tube 100e may be similar to the x-ray tubes 100a-d described above. The focus electrode 106e may include surfaces 502, 504, and 508 with corresponding locations 506 and 510 similar to surfaces 402, 404, and 408 and locations 406 and 410.

In some embodiments, the focus electrode 106e includes a protrusion 514. The protrusion extends from the third surface 508 towards the anode 102. The protrusion 514 includes the part of the focus electrode 106e that is closer to the anode 102 than any part of the field emitter 104. Part of the protrusion 514 is at the equidistant line 512 from the anode 102. All other parts of the focus electrode 106e are further from the anode 102 than that part of the protrusion 514.

In some embodiments, the protrusion 514 is associated with a local minimum radius. As the radius R, shown in view 540, on a corner of the protrusion 514 decreases, the particular feature becomes sharper. The local radius R may approach zero or approach a sharp corner. With sharper features, smaller radii, or the like, the electric field may be more concentrated in that region. The protrusion 514 may be offset from portions of the focus electrode 106e that are closer to the field emitter 104. As a result, the location of a higher electric field strength may be offset from the field emitter 104. The location of the protrusion 514 provides control over the location of a higher electric field strength and hence, the location where an arc may occur.

In some embodiments, the protrusion 514 may be disposed at or closer to the location 510 than the location 506. Thus, the protrusion 514, where an arc may be more likely to occur, may be further away from the field emitter 104.

In some embodiments, points across the third surface 508 other than the protrusion 514 are substantially equidistant from the anode 102. As a result, an electric field strength along those points may be substantially the same. However, as the protrusion 514 is at the same potential as the surface 504, the electric field strength at the protrusion 514 may necessarily be higher.

Although a focus electrode 106e that is similar to the focus electrode 106d has been used as an example of a focus electrode 106 including a protrusion 514, in other embodiments, other focus electrodes 106 may include a protrusion 514. For example, the focus electrode 106e may include a structure similar to focus electrode 106c of FIG. 3 but have a protrusion 514 that extends towards the anode 102 from a surface of the focus electrode 106e.

FIG. 6 is a cutaway view of a focus electrode according to some embodiments. As described above, multiple field emitters 104 may be present. The focus electrode 106 includes multiple openings 620. Each opening 620 is associated with one of the multiple field emitters 104. For each

of the field emitters 104, some point of the focus electrode 106f is closer to the anode 102 than that field emitter 104. The opening 620 may have a first surface 602 similar to the first surfaces 302, 402, 502, or the like, described above. The focus electrode 106f may include a second surface 604 similar to the second surfaces 304, 404, and 504 described above.

Although the openings 620 are described as being associated on a one-to-one basis with a field emitter, in other embodiments, each opening 620 may be associated with multiple field emitters. However, the focus electrode 106f may still have a point that is closer to the anode, such as the anode 102 of FIGS. 1-5, than any of those field emitters 104.

FIG. 7 is a cutaway view of a focus electrode for multiple field emitters according to some embodiments. The focus electrode 106g includes a single opening 702 formed between portions 106g-1 and 106g-2. Multiple field emitters 104 are disposed in the single opening 702. In some embodiments, a frame 704 may be disposed between the field emitters 104. In some embodiments, the frame 704 may be grounded or at the same potential as the focus electrode 106g. The focus electrode 106g may have a cross-section similar to the focus electrodes 106 described above. For example, the focus electrode 106g may have a cross-section, may include protrusions, or the like similar to focus electrodes 106a-e described above.

FIG. 8 is a cross-sectional view of a cathode assembly including a focus electrode according to some embodiments. The cathode assembly 800 includes a substrate 830. The substrate 830 may include a ceramic substrate or other insulating substrate. A conductive layer 836 such as a copper layer is disposed on the substrate 830. An emitter 844, such as carbon nanotubes, nanowires, nanorods, or the like as described above may be disposed on the conductive layer 836. Although one emitter 844 is illustrated, multiple emitters 844 may be present similar to field emitters 104 of FIG. 7. A grid 834 may be disposed over the emitter 844. A voltage may be applied between the conductive layer 836 and the grid 834 to generate electrons from the emitter 844. The grid 834 can be an intercepting type, where the electrons pass through the grid, such as a mesh, as illustrated, or the grid can be a non-intercepting type (not shown), where the electrons pass through an open aperture.

A frame 838 similar to the frame 704 of FIG. 7 may be disposed on the substrate 830. The frame 838 may also contribute to the focusing of an electron beam. The frame 838 may provide structural support for other components, such as the grid 834. A spacer (not shown) may separate the frame 838 and the grid 834, and the spacer may be conductive or insulating. The frame 838 may include multiple openings 838' associated with multiple emitters 844.

A spacer 840 may separate the frame 838 and the substrate 830. The spacer 840 may be conductive or insulating. The frame 838 may include conductive materials. A second spacer 842 is disposed on the frame 838. The second spacer 842 may be conductive or insulating. A focus electrode 106h is disposed on the second spacer 842. The focus electrode 106h may be similar to the focus electrodes 106a-g described above.

In some embodiments, the focus electrode may include a first portion 106h-1 and a second portion 106h-2 similar to the portions 106g-1 and 106g-2 of FIG. 7. Multiple openings 838' may be disposed between the portions 106h-1 and 106h-2. The portions 106h-1 and 106h-2 may extend along the emitters 844, for example parallel to the Z direction.

While the spacer 842 may be insulating, in some embodiments, the spacer 842 may be conductive or omitted. Thus, the focus electrode 106h and the frame 838 may be at the same potential.

The grid 834 or the frame 838 may provide some protection for the emitter 844 from damage due to arcs; however, due to the relatively close proximity of the grid 834 and the frame 838 to the emitter 844 and the high voltage potential of the arc, the protection may be minimal. For example, the frame 838 may be about 200 micrometers (μm) away from the emitter 844. The proximity to the emitters 838 makes the frame 838 or an attached grid less able to mitigate damage from any molten metal or metal vapor caused by the arc. In addition, a material of the spacer 842 or other structure may be damaged if an arc occurs near the frame 838. Accordingly, moving a location where an arc may occur to further from the emitter 844 and the frame 838 on the focus electrode 106h may reduce damage that may occur to the emitter 844, frame 838, spacer 842, or other similar structures due to an arc.

FIG. 9 is a block diagram of an x-ray imaging system according to some embodiments. The x-ray imaging system 900 includes an x-ray source 902 and detector 910. The x-ray source 902 may be similar to an x-ray tube 100a-e as described above. The x-ray source 902 is disposed relative to the detector 910 such that x-rays 920 may be generated to pass through a specimen 922 and detected by the detector 910. In some embodiments, the detector 910 is part of a medical imaging system, non-destructive testing system, or the like. In other embodiments, the x-ray imaging system 900 may include a portable vehicle scanning system as part of a cargo scanning system.

Some embodiments include an x-ray tube, comprising: a field emitter 104 including an emission surface; an anode 102; and a focus electrode 106, 106a-h disposed between the field emitter 104 and the anode 102; wherein: the focus electrode 106, 106a-h includes: a first surface 302, 402, 502, 602 that is substantially perpendicular to the field emitter 104 emission surface and nearest to the field emitter 104; a second surface 304, 404, 504, 604 that is axially nearest to the anode 102, wherein the field emitter 104 and the anode 102 form an axis; and a third surface 308, 408, 508 that extends between the first surface 302, 402, 502, 602 and the second surface 304, 404, 504, 604; and a first location 406, 506 on the focus electrode 106, 106a-h between the first surface 302, 402, 502, 602 and the third surface 308, 408, 508 is further from the anode 102 than a second location 410, 510 on the focus electrode 106, 106a-h between the third surface 308, 408, 508 and the second surface 304, 404, 504, 604.

In some embodiments, the second location 410, 510 on the focus electrode 106, 106a-h is further from a center of the field emitter 104 than another part of the focus electrode 106, 106a-h.

In some embodiments, the focus electrode 106, 106a-h is grounded.

In some embodiments, the focus electrode 106, 106a-h further comprises a protrusion 514 extending towards the anode 102.

In some embodiments, the protrusion 514 is closer to the second location 410, 510 on the focus electrode 106, 106a-h and the anode 102 than the first location 406, 506 on the focus electrode 106, 106a-h.

In some embodiments, the focus electrode 106, 106a-h is shaped such that during operation, a point of highest electric field strength is disposed at the second location 410, 510.

In some embodiments, the second surface **304, 404, 504, 604** extends radially and axially away from the first surface **302, 402, 502, 602** relative to the axis.

In some embodiments, the x-ray tube further comprises: a cathode structure including: a substrate wherein the field emitter **104** is disposed on the substrate; a frame disposed on the substrate over the field emitter **104**; and the focus electrode **106, 106a-h** wherein the focus electrode **106, 106a-h** is disposed on the frame.

In some embodiments, the field emitter **104** is one a multiple field emitter **104s** disposed on the substrate; the frame includes multiple openings, each opening corresponding to one of the multiple field emitter **104s**; the focus electrode **106, 106a-h** includes a first portion and a second portion; and the openings of the frame are disposed between the first portion and the second portion.

In some embodiments, points across the second surface **304, 404, 504, 604** are substantially equidistant from the anode **102**.

Some embodiments include an x-ray tube, comprising: a cathode structure **800** including a field emitter **104**; an anode **102**; and a focus electrode **106, 106a-h** disposed between the field emitter **104** and the anode **102**; wherein the focus electrode **106, 106a-h** is disposed relative to the field emitter **104** and the anode **102**, and the focus electrode **106, 106a-h** is shaped such that during operation, a point of highest electric field strength on the cathode structure is closer to the focus electrode **106, 106a-h** than the field emitter **104**.

In some embodiments, the point of highest electric field strength is further from a center of the field emitter **104** than another part of the focus electrode **106, 106a-h**.

In some embodiments, the focus electrode **106, 106a-h** is grounded.

In some embodiments, the field emitter **104** and the anode **102** form an axis; and the focus electrode **106, 106a-h** comprises: a first surface **302, 402, 502, 602** extending substantially parallel to the axis; a second surface **304, 404, 504, 604** extending radially away from the first surface **302, 402, 502, 602** relative to the axis.

In some embodiments, a first location on the focus electrode **106, 106a-h** is between the first surface **302, 402, 502, 602** and the second surface **304, 404, 504, 604**; and the focus electrode **106, 106a-h** is shaped such that during operation, a point of highest electric field strength is disposed at the first location.

In some embodiments, the field emitter **104** and the anode **102** form an axis; and the focus electrode **106, 106a-h** comprises: a first surface **302, 402, 502, 602** extending substantially parallel to the axis; a second surface **304, 404, 504, 604** extending radially away from the first surface **302, 402, 502, 602** relative to the axis; a third surface **308, 408, 508** extending radially and axially away from the first surface **302, 402, 502, 602** relative to the axis towards the second surface **304, 404, 504, 604**; and a first location **306, 406, 506** on the focus electrode **106, 106a-h** between the first surface **302, 402, 502, 602** and the third surface **308, 408, 508**; and a second location **410, 510** on the focus electrode **106, 106a-h** is between the third surface **308, 408, 508** and the second surface **304, 404, 504, 604**.

In some embodiments, the focus electrode **106, 106a-h** is shaped such that during operation, a point of highest electric field strength is disposed at the second location **410, 510**.

In some embodiments, points across the second surface **304, 404, 504, 604** are substantially equidistant from the anode **102**.

Some embodiments include an x-ray tube, comprising: means for emitting electrons towards an anode; and means

for focusing electrons emitted from the means for emitting electrons towards the anode, comprising: means for increasing an electric field strength at the means for focusing electrons beyond an electric field strength at the means for emitting electrons.

Examples of the means for emitting electrons towards an anode include the cathode structure **800**, the field emitter **104**, the grid **834**, or the like. In an example, the means for emitting electrons towards an anode can include at least three field emitters **104**.

Examples of the means for focusing electrons emitted from the means for emitting electrons towards the anode include the focus electrode **106, 106a-h**, and the frame **704, 838**.

Examples of the means for increasing an electric field strength at the means for focusing electrons beyond an electric field strength at the means for emitting electrons include surfaces **302, 402, 502, 602, 408, 508**, locations or edges **406, 506**, the protrusion **514**, or the like

In some embodiments, the means for focusing electrons further comprises: means for positioning a point of maximum electric field strength on the means for focusing electrons further from the means for emitting electrons than a closest part of the means for focusing electrons to the means for emitting electrons. Examples of the means for positioning a point of maximum electric field strength on the means for focusing electrons further from the means for emitting electrons than a closest part of the means for focusing electrons to the means for emitting electrons include the location **410** and **510**, the protrusion **514**, or the like.

Although the structures, devices, methods, and systems have been described in accordance with particular embodiments, one of ordinary skill in the art will readily recognize that many variations to the particular embodiments are possible, and any variations should therefore be considered to be within the spirit and scope disclosed herein. Accordingly, many modifications may be made by one of ordinary skill in the art without departing from the spirit and scope of the appended claims.

The claims following this written disclosure are hereby expressly incorporated into the present written disclosure, with each claim standing on its own as a separate embodiment. This disclosure includes all permutations of the independent claims with their dependent claims. Moreover, additional embodiments capable of derivation from the independent and dependent claims that follow are also expressly incorporated into the present written description. These additional embodiments are determined by replacing the dependency of a given dependent claim with the phrase "any of the claims beginning with claim [x] and ending with the claim that immediately precedes this one," where the bracketed term "[x]" is replaced with the number of the most recently recited independent claim. For example, for the first claim set that begins with independent claim **1**, claim **4** can depend from either of claims **1** and **3**, with these separate dependencies yielding two distinct embodiments; claim **5** can depend from any one of claim **1, 3, or 4**, with these separate dependencies yielding three distinct embodiments; claim **6** can depend from any one of claim **1, 3, 4, or 5**, with these separate dependencies yielding four distinct embodiments; and so on.

Recitation in the claims of the term "first" with respect to a feature or element does not necessarily imply the existence of a second or additional such feature or element. Elements specifically recited in means-plus-function format, if any, are intended to be construed to cover the corresponding

11

structure, material, or acts described herein and equivalents thereof in accordance with 35 U.S.C. § 112(f). Embodiments of the invention in which an exclusive property or privilege is claimed are defined as follows.

The invention claimed is:

1. An x-ray tube, comprising:
a field emitter including an emission surface;
an anode; and
a focus electrode disposed between the field emitter and the anode;
wherein:
the focus electrode includes:
a first surface that is substantially perpendicular to the field emitter emission surface and nearest to the field emitter; 15
a second surface that is axially nearest to the anode, wherein the field emitter and the anode form an axis; and
a third surface that extends between the first surface and the second surface; 20
a first location on the focus electrode between the first surface and the third surface is further from the anode than a second location on the focus electrode between the third surface and the second surface; and 25
the focus electrode further comprises a protrusion extending towards the anode.
2. The x-ray tube of claim 1, wherein:
the second location on the focus electrode is further from a center of the field emitter than another part of the focus electrode. 30
3. The x-ray tube of claim 1, wherein:
the focus electrode is grounded.
4. The x-ray tube of claim 1, wherein:
the protrusion is closer to the second location on the focus electrode and the anode than the first location on the focus electrode. 35
5. The x-ray tube of claim 1, wherein:
the focus electrode is shaped such that during operation, a point of highest electric field strength is disposed at the second location. 40
6. The x-ray tube of claim 1, wherein:
the second surface extends radially and axially away from the first surface relative to the axis. 45
7. The x-ray tube of claim 1, further comprising:
a cathode structure including:
a substrate wherein the field emitter is disposed on the substrate;
a frame disposed on the substrate over the field emitter; and 50
the focus electrode wherein the focus electrode is disposed on the frame.
8. The x-ray tube of claim 7, wherein:
the field emitter is one of multiple field emitters disposed on the substrate;
the frame includes multiple openings, each opening corresponding to one of the multiple field emitters; 55
the focus electrode includes a first portion and a second portion; and
the openings of the frame are disposed between the first portion and the second portion.
9. The x-ray tube of claim 1, wherein:
points across the second surface are substantially equidistant from the anode. 60
10. An x-ray tube, comprising:
a cathode structure including a field emitter;
an anode; and

12

a focus electrode disposed between the field emitter and the anode, the focus electrode comprising a protrusion extending towards the anode;

wherein the focus electrode is disposed relative to the field emitter and the anode, and the focus electrode is shaped such that during operation, a point of highest electric field strength on the cathode structure is closer to the focus electrode than the field emitter and disposed on the protrusion of the focus electrode.

11. The x-ray tube of claim 10, wherein:
the point of highest electric field strength is further from a center of the field emitter than another part of the focus electrode.

12. The x-ray tube of claim 10, wherein:
the focus electrode is grounded.

13. The x-ray tube of claim 10, wherein:
the field emitter and the anode form an axis; and
the focus electrode comprises:

a first surface extending substantially parallel to the axis;
a second surface extending radially away from the first surface relative to the axis.

14. The x-ray tube of claim 13, wherein:
a first location on the focus electrode is between the first surface and the second surface; and
the focus electrode is shaped such that during operation, a point of highest electric field strength is disposed at the first location.

15. The x-ray tube of claim 10, wherein:
the field emitter and the anode form an axis; and
the focus electrode comprises:

a first surface extending substantially parallel to the axis;
a second surface extending radially away from the first surface relative to the axis;
a third surface extending radially and axially away from the first surface relative to the axis towards the second surface; and
a first location on the focus electrode between the first surface and the third surface; and
a second location on the focus electrode is between the third surface and the second surface.

16. The x-ray tube of claim 15, wherein:
the focus electrode is shaped such that during operation, a point of highest electric field strength is disposed at the second location.

17. The x-ray tube of claim 13, wherein:
points across the second surface are substantially equidistant from the anode.

18. An x-ray tube, comprising:
means for emitting electrons towards an anode; and
means for focusing electrons emitted from the means for emitting electrons towards the anode, comprising:
means for increasing an electric field strength at the means for focusing electrons beyond an electric field strength at the means for emitting electrons including a protrusion extending towards the anode.

19. The x-ray tube of claim 18, wherein the means for focusing electrons further comprises:
means for positioning a point of maximum electric field strength on the means for focusing electrons further from the means for emitting electrons than a closest part of the means for focusing electrons to the means for emitting electrons.

20. An x-ray tube, comprising:
a plurality of field emitters, each field emitter including an emission surface;

an anode;
a focus electrode disposed between at least one of the plurality of field emitters and the anode; and
a cathode structure including:
a substrate wherein the at least one of the field emitters 5
is disposed on the substrate;
a frame disposed on the substrate over the at least one
of the field emitters; and
the focus electrode disposed on the frame
wherein: 10
the focus electrode includes:
a first surface that is substantially perpendicular to an
emission surface of the at least one of the field
emitters and nearest to the at least one of the field
emitters; 15
a second surface that is axially nearest to the anode,
wherein the at least one of the field emitters and
the anode form an axis; and
a third surface that extends between the first surface
and the second surface; 20
a first location on the focus electrode between the first
surface and the third surface is further from the
anode than a second location on the focus electrode
between the third surface and the second surface;
the frame includes multiple openings, each opening 25
corresponding to one of the field emitters;
the focus electrode includes a first portion and a second
portion; and
the openings of the frame are disposed between the first
portion and the second portion. 30
